UNITED STATES PATENT OFFICE.

EDWARD R. BRODTON, OF MOBILE, ALABAMA, ASSIGNOR OF THIRTEEN-FIFTEENTHS TO
GEORGE H. FONDE AND ERNEST E. WAGAR, OF MOBILE, ALABAMA.

RAILWAY SIGNALING APPARATUS.

No. 902,553.

Specification of Letters Patent.

Patented Nov. 3, 1908.

Application filed November 19, 1907. Serial No. 402,853.

To all whom it may concern:

Be it known that I, EDWARD R. BRODTON, a citizen of the United States, residing at Mobile, in the county of Mobile and State of Alabama, have invented a new and useful Railway Signaling Apparatus, of which the following is a specification.

This invention has reference to improvements in railway signaling apparatus, being designed more particularly for the automatic transmission of danger signals both in front and behind a train or from a switch or from a block station or from some portion of the railroad liable to dangerous conditions, and these signals are in accordance with the present invention transmitted without the aid of line conductors by what is known as the wireless system of transmission of signals.

With wireless systems of signal transmission for railways as heretofore proposed there is the constant danger of false signals being given from wireless telegraphic stations located adjacent to or even a considerable distance from the railroad. The present invention is designed to avoid such unauthorized operation of the signals, whether the same be accidental or whether it be attempted from a malicious desire to interfere with the proper operation of the railroad.

In accordance with the present invention the signal indicating devices are inoperative to produce a proper signal unless there be two or more wave trains propagated, the said wave trains having different characteristics and simultaneously active except that one wave train may overlap the other wave train at both ends.

The invention also includes two receiving means adapted to the characteristics of the coacting transmitters so arranged that one will respond to one of the wave trains, and the other will respond to the other wave train, but the second transmitter will not be operative to the second (and shorter) wave train until the first receiver has acted to an extent sufficient to couple up the second receiver in a manner to be responsive to the second wave train.

The invention contemplates the sending of cautionary signals which will notify the engineman of a dangerous condition, either ahead or approaching from the rear, demanding that his train be brought to a standstill, but should the signals be disregarded, and they sometimes are, then provision is made

for the sending of a second signal which will automatically operate the throttle and brakes so as to bring the train to a standstill outside the volition of the engineman. It is within the scope of the invention to provide means whereby two or more cautionary signals may be given before the emergency parts are brought into operation. In order that the engineman may be made aware of the operation of the signals in an obtrusive manner, both visual and audible signals may be used. Furthermore, provision is made for the continuous operation of the precautionary signals and of the emergency mechanisms, even though the wave trains coming from a sending station have ceased, and these signals will continue to operate until they are again set into condition to receive still other signals.

The invention further provides means whereby the engineman may be aware of the direction, whether ahead or to the rear, from which the signals are coming.

In order that the engineman, having himself operated the emergency appliances without the danger condition being present, cannot then claim that the devices were operated automatically in the manner provided for, the invention also comprises an automatic register which will operate only when the emergency apparatus has been properly operated by impulses sent out from some sending station and received on the engine in the manner intended by the system.

The invention comprises, likewise, means whereby wave trains peculiar to the railway train or station may be continuously propagated whether the train be in motion or standing still.

In addition to these several features there is included in the invention a telephonic system whereby after the train has received a cautionary danger signal and has been brought to a standstill the engineman may call up another train or station at the point of danger from which the danger signal emanated and receive telephonically such information as may be necessary.

In order to carry out the various propositions of the present invention I have devised the system which will be best understood by a consideration of the following detailed description taken in connection with the accompanying drawings forming a part of this specification, in which drawings,—

Figure 1 is a diagram of the circuit connec-

tions on an engine, both for sending and receiving signals and messages. Fig. 2 is a detail view on a larger scale than that shown in Fig. 1, illustrating the means for coupling up the wave generating apparatus for the propagation of the messages. Figs. 3, 4 and 5 are different forms of cam structures for causing the circuit-closing devices on the transmitters to be operated. Figs. 6 and 7 are two views of the automatic register for the emergency conditions showing different phases of its operation. Fig. 8 is a detail view of the mechanism for indicating in what direction the signal has been transmitted. Fig. 9 is a detail showing the means for holding certain of the signal devices against accidental operation due to the shocks and jars incident to the movement of a locomotive. Fig. 10 is a detail view of the governor index. Fig. 11 is a diagrammatic elevation of a semaphore or target signal to be used in place of certain lamp signals. Figs. 12 and 13 are side and plan views, respectively, of a supporting means for the apparatus constituting an absorber for mechanical shocks. Fig. 14 is a detail view of one of the absorber springs. Fig. 15 is a diagrammatic view on a larger scale than shown in Fig. 1 of the means under the control of the receivers of the trains of ether waves for producing the signals. Fig. 16 is a diagrammatic view of the sending apparatus wherein a dynamo electric generator is used in place of batteries for supplying the current.

Before entering into a description of the details of the system, it may be well to state that upon each engine there is located two transmitters capable of propagating through an aerial wave trains having different characteristics, as for instance, wave trains may be made up of waves of different periodicity. Upon each engine there is a constantly running mechanism capable of closing the circuit to one of the transmitters to cause a propagation of a train of waves of some predetermined length, and the same mechanism is arranged to cause the closing of the circuit of the second transmitter at a predetermined time after the closing of the first transmitter circuit and to open the second transmitter circuit before the first transmitter circuit has been opened, although the opening of the two circuits may be coincident.

Also upon the engine there are located two receiver circuits, one of which is responsive to the first circuit of some distant transmitter and the other of which is responsive to the second circuit of some distant transmitter, and these two circuits, when working conjunctively, and only when working conjunctively, control a signal circuit through which one, two or more cautionary signals may be transmitted, and then, on the failure of the engineman to take heed of said cautionary signals, to ultimately cut off the steam

at the throttle and apply the brakes. There is likewise provided on the engine a telephonic system which usually is made operative after the engine has come to a standstill.

Each engine is supplied with such transmitting and receiving systems. Where there is along the line of the railroad certain localities subject to dangerous conditions such as avalanches, washouts, landslides, or the like, then these localities are provided with the transmitters only, but block stations may be provided with the transmitting and receiving circuits which will give signals without of course including the emergency structures and may also include the telephone system.

Now, referring more particularly to Fig. 1, there is shown an aerial conductor 1 with an expanded head 2 over which is located a sheath 3, the aerial 1 being of course of an altitude not greater than the height of an engine, but this will be found sufficient for the transmission of messages for several miles with an apparatus otherwise properly designed. The danger zone thereby has an extent equal at least to the usual distance between block stations and ample for the stoppage of any train before the point of danger is reached.

Each engine or sending station is provided with two Ruhmkorff coils 4 and 5 which, however, may be taken as indicative of any suitable source of Hertzian waves. Since the zone of propagation need not extend more than a very few miles, these coils or other propagating source may be quite small. Each coil is provided with a spark gap 6 connected on one side by a conductor 7 to the aerial 1 and on the other side by a conductor 8 to the ground conductor 9, connected to one of the axles 10 of the engine or otherwise grounded.

First, considering the coil 4, its primary circuit is through a conductor 11 and rheostat 12 to one side of a battery 13, thence to one conductor 14 of a plug 15. The other side of the primary of the coil 4 is connected by a conductor 16 to a contact spring 17 mounted upon, but insulated from, a small electric motor 18. The spring 17 has its free end resting upon a post 19 fast upon the base 20 upon which the motor is mounted, and this free end extends beyond the post 19, as indicated at 21. Above the spring 17, but insulated therefrom, is another spring-arm 22, and above the arm 22, but insulated therefrom, is still a third spring-arm 23. The spring-arm 22 has the free end formed into a head 24 immediately above the post 19 but normally out of contact with the arm 17. The arm 23 has a head 25 immediately above, but out of contact with, the head 24, and this last-named arm 23 may be also provided with a manipulating button 26 to which reference will be had later. The spring-arm 22 is connected by a conductor 27 to a spring

clip 28 with which the plate 14 of the plug 15 may be brought into contact.

One side of the primary winding of the coil 5 is connected by a conductor 29 through a 5 rheostat 30 to one side of the battery 13, and the other side of the primary winding of the coil 5 is connected by a conductor 31 to the spring-arm 23 before referred to.

The post 19 carries a shaft 32, best shown 10 in Fig. 2, and this shaft may be driven by a train of gears 33, 34, 35 and 36, or any other arrangement of reducing gears from the armature shaft 37 of the motor 18. The shaft 32 carries a disk 38 formed with a cam projection 39 having a portion 40 in its periphery in the form of an arc struck from the center of the disk 38 with a cam face 41 of considerable length reaching from the face 40 to the periphery of the disk. At the other end 15 of the face 40 the cam recedes to the periphery of the disk by a somewhat sudden slope 42. The foregoing cam is best shown in Fig. 3 where only one cam 39 is indicated. In Fig. 4, there are three such cam surfaces shown, and in Fig. 5 these cam surfaces are shown upon a belt 43 passed around two spaced rollers 44, one of which may replace the disk 38 upon the shaft 32 and the other of which may be mounted some distance therefrom as an idler. The armature shaft 37 at the end remote from that carrying the gear 36 is provided with another gear 45 meshing with a pinion 46 upon one end of a shaft 47 mounted in suitable bearings on standards 35 48. This shaft 47 has secured to it one end of a ball governor 49 of common type, the other end of which slides upon the shaft and carries a friction disk 50, and an adjustable friction head 51 mounted upon a screw 52 is carried by a post or standard 53. The friction head 51 is so adjusted that when the speed of the motor, and consequently of the governor, reaches a certain predetermined limit, the disk 50 is brought into contact with the head 51 until the centrifugal force acting on 45 the governor and the friction generated between the disk and head balance so that the motor is maintained at a certain fixed speed. In order that the generator may be set at any desired speed the screw 52 is provided with a pointer 54 and index plate 55, which latter is fixed to the standard 53. This indicator disk is best shown in Fig. 10.

One terminal of the motor 18 is connected 55 by a conductor 56 to a battery 57, the other side of which latter is connected by a conductor 58 to a spring contact 59 with which one element 60 of the plug 15 may make contact, and this element is shown as connected 60 by a conductor 61 with the other side of the motor. It is to be understood, however, that the plug 15 need not be connected to the conductor 61 and the battery 13, as indicated in the drawings, since these parts may 65 of course be connected to suitable terminals

so that the plug when inserted will complete the respective circuits.

Now, let it be assumed that the plug 15 is caused to close the circuits of the batteries 13 and 57 at the terminals controlled by the 70 plug. The armature of the motor 18 begins to rotate and speeds up until it reaches the speed determined by the governor 49, at which speed it continues to rotate so long as the plug is in position. Every time a cam 39 75 engages the end 21 of the spring-arm 17 the circuit is closed between this arm and the arm 24. This energizes the primary of the coil 4 and the secondary is thus caused to generate currents in the manner usually employed for wireless transmission and so a train of waves is propagated and emanates from the head 2 of the aerial 1. After the coil 4 has started then the cam further acts upon the arm 21 and head 24 to bring the 80 latter ultimately into contact with the head 25, when the coil 5 is energized and another train of waves is propagated from the head 2 of the aerial. The second set of waves may be characteristically different from the first 85 set of waves and because of the shape of the cam 39 both sets of waves are continued for a time until the shoulder 42 is reached, when the head 24 is lowered from the head 25 and then quickly the circuit is broken between 90 the arm 21 and the head 24. There is thus propagated a train of waves of a certain characteristic followed after a predetermined time limit by a second train of waves of other characteristics, and the two trains are then 100 coincident in time for a predetermined period, when the second train of waves ceases and immediately afterward the first train of waves ceases. The rheostats 12 and 30 are useful in adjusting the current supplied to 105 the coils 4 and 5.

For certain purposes the speed of transmission of the trains of waves may be varied by varying the speed of the motor so that no two railway trains or stations will be identical, and by this means the different trains or stations may be recognized at the different receiving stations. Furthermore, for certain other purposes railway trains going in one direction may send out the impulses, 110 say once during a certain time period, and those going in another direction may send out two or three trains of waves during a certain time period, or they may send out groups of trains of waves with a longer or shorter interval between these groups. For this purpose a railroad train may have a disk such as shown in Fig. 4, with the cams thereon grouped in a certain manner to indicate that the railroad train is moving in one 115 direction while in the other direction this disk may have the cam as in Fig. 3. These groupings are simply illustrative and may be varied in many ways, as the conditions may demand. Or one train may have a cam 120

which will send out impulses during a short time period and another train going in the opposite direction may have a cam two or three times as long or of greater length so that the time interval during which the impulses or trains of waves are propagated is materially lengthened.

Referring again to Fig. 1, the aerial 1 is branched off through a conductor 62, including a rheostat 63, to a coherer 64, the other side of which is connected by a conductor 65 to the ground conductor 9. The coherer 64 is connected on one side by a conductor 66 to a relay 67, the magnets of which are included in a conductor 68 leading to a battery 69 connected on the other side by a conductor 70, back to the conductor 65, thus completing a circuit through the relay which becomes energized when the trains of waves pass through the coherer in the usual manner. The relay controls another circuit comprising a conductor 71 including in its circuit a lamp 72 and a battery 73, from which latter extends a conductor 74 to an electro magnet 75, the other side of which is connected by a conductor 76 to an indicator 77 to be herein-after described, and from this indicator there extends another conductor 78 to a bell 79 from which there is still another conductor 80 leading back to the relay. The hammer of the bell 79 may operate as a tapper for decohering the coherer. The magnet 75 controls an armature 81 against the action of a spring 82, for a purpose which will presently appear. The aerial 1 has likewise connected to it a conductor 83 including a rheostat 84 and leading to another coherer 85 from which there extends a conductor 86 to the ground wire 9.

In circuit with the coherer is a relay 89, the magnets of which are connected by a conductor 90 with a battery 91, and this battery in turn is connected with a conductor 92 to the conductor 86 while the coherer is likewise connected by a conductor 93 to the relay magnets. The circuit controlled by the relay 89 comprises a conductor 94 including a lamp 95 and leading to a battery 96 from which there is a conductor 97, and branched over from this last-named conductor 97 there is another conductor 98 leading to a magnet 99 which may be mounted upon a board 100, and from the magnet 99 leads a conductor 101 to a terminal 102 in the path of an armature lever 103, which in turn is connected by a conductor 104 and back to the contacts of the relay 89, and this conductor 104 includes a bell 105, the clapper of which serves as a tapper for the coherer 85. Mounted upon the board 100 is a post 106 upon which the armature lever 103 is pivoted, and this lever extends beyond its pivot, as shown at 107, and carries a spring pawl 108 operating a ratchet 109 which may be used to actuate the register,

which, however, is not shown. Mounted upon the board 100 is another post 110 carrying a spring contact finger 111 normally out of contact with the armature lever 103 but in the path thereof. Pivoted to the board 100 is an arm 112 of insulating material, or duly insulated, and this arm is formed with a lug 113 against which the armature lever 103 abuts when the said lever is in inoperative position, that is when the magnet 99 is not energized and the lever is upheld by a spring 114. The arm 112 is under the control of a spring 115 secured at one end to the arm and at the other end to the post 106 and tending to draw the arm 112 toward the end of the armature lever.

When the magnet 99 is energized the armature lever is drawn downward against the action of its spring 114, and the lug 113 is so shaped that as soon as the armature lever is drawn down but a short distance, the under edge 116 of this lug acts as a cam surface on the armature lever, and the arm 112 under the action of the spring 115 forces the lever 103 downward away from the contact 102 and into engagement with the spring finger 111, causing the latter to yield to a certain extent. The armature lever 103 carries a contact terminal 117, in the path of which is a fixed terminal 118 connected to the conductor 119, which latter leads to another armature lever 120 mounted upon a post 121 on a board 122 carrying another magnet 123 and another post 124 on which is still another spring finger 125 in the path of the lever 120, and the board 122 likewise carries the arm 126 similar to the arm 112, and this arm 126 has a lug 127 like the lug 113 and is under the control of a spring 128 like the spring 115. The armature lever 120 is also under the control of a spring 129, and has beyond its pivot an extension 130 carrying a spring pawl 131 actuating a ratchet 132.

The spring finger 111 is connected to a conductor 133 leading to a bell 134 and lamp 135 from which the circuit is continued through a conductor 136 to a battery 137 and back by a conductor 138 to the post 106, before referred to.

The spring finger 125 forms one terminal of a circuit embracing a conductor 139 leading to a magnet 140, the other side of which is connected by a conductor 141 including a switch 142 to the conductor 97, before referred to. This last-named conductor 97 also leads to one side of the magnet 123, the other side of which is connected by a conductor 143 to a terminal 144 in the path of the armature 120. The magnet 140 controls an armature 145 in opposition to a spring 146, and this armature has in its path a certain terminal 147 connected by a terminal 148 to one side of a motor 149, the other side of which is connected by a conductor 150 to a register 151, the other side of which 130

register is connected by a conductor 152 to a battery 153, and this battery is connected by a conductor 154 to the armature lever 145. The motor 149 is connected, though not so shown, to the throttle and air brake system of the engine, this motor being driven by the battery 153; and when set in motion the motor will close the throttle by shutting off steam from the engine and at the same time cause the air brakes to be applied. The switch 142 is connected by any suitable means such, for instance, as a link 155, to the throttle of the engine so that when this throttle has been closed the circuit to the magnet 140 is then opened; and the motor 149 is thereby stopped from further action.

In order that the receiver circuits may be prevented from responding to the impulses sent out by the transmitters at the same station or engine the spring arm 17 is connected by a conductor 232 to and forms part of the battery circuit of the coherer 64, and the post 19 is connected by another conductor 233 to, and forms part of the circuit of the coherer 64 so that the battery circuit of this coherer 64 is cut out whenever the end 21 of the arm 17 is raised from off the post 19, this post being of conducting material. Furthermore, in the path of the armature 81 there is a contact 87 connected by a conductor 88 to and forming part of the circuit of the battery 91, and another conductor 234 leads to the armature 81 so that the battery circuit of the coherer 85 is closed only when the magnet 75 is energized.

The different sending apparatus located at different points are differently timed so that no two will synchronize, and it is only occasional that the sending apparatus of a station or locomotive would be operating at the time a train of waves was being sent from some other station, and if such an event should transpire then the next set of waves would reach the receiving apparatus in the interval between the operations of the transmitter or transmitters. For all practical purposes the receivers are in condition to receive the emanated waves from a distance but are always cut out from the effect of the waves generated at the same station where the receivers are located.

Now, assume that a railroad engine equipped as indicated by Fig. 1 is traveling upon the tracks, or it may be standing still upon the track. At intervals determined by the speed of the motor 18 there are propagated two sets of wave trains in the manner already set forth, and these wave trains will actuate receivers upon a train within the zone of activity of these waves or if such receivers be located at a block station then the indications will be received at such block station. Assume, further, that another train is traveling upon the track either toward the first train from the rear or from the front or

let it be supposed that some dangerous condition has developed upon the line of way and that by such dangerous condition the transmitter, such as shown in Fig. 1, has been set in operation and the train under consideration is within the danger zone. If a single impulse is picked up by the aerial 1 and passes through the coherer 64 then the light 72 is caused to flash and the bell 79 will give an audible signal and the circuit of the second coherer will be closed by the armature 81 making contact with the terminal 87. At the same time the indicator 77, which will be hereinafter described with reference to Fig. 8, will give an indication which, as will hereinafter appear shows from which direction, whether in front or to the rear of the train, the signal has been sent. If but one train of waves be sent, such as the receiving circuit controlled by the coherer 64 will respond to, then there is simply a flash of the lamp and ring of the bell, and this might occur even from an ordinary wireless telegraphic sending station anywhere within the zone of influence of such station. Under these circumstances, nothing further will happen and the engineer will understand that the system has picked up some fugitive message not transmitted from any danger zone along the railway. If, however, the proper transmitter has been acting then as soon as the first coherer has become active and the relay circuit through the magnet 75 has been energized so that the armature 81 closes the circuit of the second coherer through the terminal 87, then

the second train of waves following immediately upon and then coincident with the first train of waves, acting through the coherer 85 closes the relay circuit and the lamp 95 will glow and the magnet 99 is energized, and the bell 105 will also give a signal. Immediately upon energization of the magnet 99 the armature lever 103 is drawn toward this magnet and its free end rides down the lug 113, when it is, by the action of the spring 115, mechanically brought and held in contact with the spring finger 111 and in contact with the circuit terminal 118. The lug 113 is so shaped as to cause the armature lever 103 to be moved during an appreciable period of time before the circuit is closed at the terminal 118, and this period of time is longer than the time period of the second train of waves. In the meantime the circuit through the magnet 99 is broken at the terminal 102 and the circuit including this magnet becomes inactive. However, a new circuit is established through the magnet 123 and parts controlled thereby, but in the meantime the circuit has become broken at the relay 89 and consequently the said circuit is inactive. However the circuit from the terminal 111 through the bell 134 and the lamp 135 remains closed being held closed by the engagement of the lug 113 over the armature lever 103, and the bell 134 con-

tinues to ring and the lamp 135 to glow until its circuit is manually broken by the engineman or some other authorized person. When the bell 134 rings and the lamp 135 glows the 5 engineman then understands that there is a dangerous condition either ahead or behind and his duty is to immediately stop his train. However, some enginemen do not always obey orders or observe signals, and in 10 order that the failure of the engineman to do his duty under the conditions may not endanger the safety of the train, provision is made for the actuation of the emergency devices on the reception of the second signal, 15 which is sent out automatically within a brief time after the first signal. Since the disk 38 continues to rotate the cam 39 will again cause the propagation of the two trains of waves. Now, however, the circuit controlled 20 by the coherer 64 is again closed and the circuit controlled by the coherer 85 is likewise closed but instead of acting through the magnet 99, which is now out of circuit, the new circuit is completed through the 25 magnet 123, when the same cycle of operations already described is effected by the parts controlled by the magnet 123 and the circuit through the magnet 140 is completed. This causes the closure of the circuit of the 30 motor 149 through the terminal 147 and armature lever 145 and the motor will close the throttle and actuate the air brake system, after which the circuit of the magnet 140 is automatically opened at the switch 142.

35 So far, the engineman is ignorant of the trouble or the location of the trouble except that the register 77 has indicated to him whether the danger zone is to the rear of the train or whether his train is approaching 40 such danger zone. In order that the engineman may have communication with some one at the point of danger, there is provided a telephone system shown in connection with the diagram, Fig. 1.

45 Connected to the aerial 1 is a conductor 156 terminating in a contacting stake 157, and this conductor 156 is of sufficient length so that the stake 157 may be carried some 50 distance from the engine and then inserted in the ground. This conductor 156 is designed simply to ground the aerial side of the coil 5, the other side of which is grounded through the axle 10. Branched off from the conductor 156 is another conductor 158 leading 55 from one side of the telephone receiver 159, the other side of which is connected by a conductor 160 to the ground conductor 9. The receiver is thus, when the stake 157 is in the ground, included in a circuit grounded at 60 each end and will receive telephonic messages from a telephonic transmitter circuit similarly grounded at a distance of some miles, even when the grounds at the receiver and transmitter ends are separated only by a 65 short distance.

Branched off from the plug side of the battery 13 is a conductor 161 leading to a terminal 162 in the path of the usual receiver-hook 163, and adjacent to this terminal 162 is another terminal 164 leading to one side of a transmitter 165 which may be of the usual long distance type. The other side of this transmitter 165 is connected to a terminal 166 in the path of a switch 167 connected to the conductor 160. This switch and terminal 166 are only diagrammatically represented in Fig. 1, but it will be understood that they are both carried by the receiver in convenient position to be manipulated by the hand of the user holding the receiver. 70 Branched off from the conductor 158 is another conductor 168 leading to the conductor 31 so that when the switch 167 is closed under the terminal 166 there is a local circuit established between the transmitter 165 and the 80 primary winding of the coil 5, and this coil therefore acts in the usual manner of an ordinary telephone coil, but because of its size and the conditions under which it operates it acts with greater vigor than the ordinary telephone 85 coil. These coils, however, are in practice provided with condensers and I have found that it is necessary to eliminate the condenser from the circuit when telephone messages are to be sent, but the condenser is maintained in 90 the circuit when the coil is used for the propagation of Hertzian waves. Therefore there is placed in operative relation to the hook 163 two terminals 169 and 170. The terminal 169 is connected by a conductor 171 to the 100 condenser 172 of the coil 5, on one side of the said condenser, and the terminal 170 is connected by a conductor 173 to the other side of the condenser, so that the condenser is cut out of circuit when the receiver is off the 105 hook and is in the circuit when the receiver is on the hook.

The telephone is designed for use usually when the engine has come to a standstill, for then any signals received are inoperative to 110 effect the controlling mechanism of the engine. Therefore, under these conditions the engineman may grasp the knob 26 and close the circuits between the heads 24 and 25 and the spring arm 17 and send in rapid succession trains of waves to affect the bells 79 and 105 after the manner of telephone bells, and such a signal will be understood at the station or on the engine affected as a telephone signal and then the telephones may be used 115 in the ordinary manner for the transmission of information vocally.

When the telephone is being used it is advisable that the motor 18 be cut out of circuit without, however, cutting out the battery 13, since that battery is used in the telephone transmission. Therefore there is provided in the motor circuit a switch 174 so that this circuit may be broken when desired.

In Fig. 8 there is shown a diagrammatic 130

representation of a means whereby the indicator 77 may be made to show whether the point from which the danger signal emanated was in front or behind the receiving train.

5 This indicator is provided with a pointer 175 and an index 176 over which the pointer is capable of swinging. The pointer is actuated by a solenoid 177 included between the conductors 76 and 78, and when the solenoid 10 is energized its armature 178 is drawn in, and through a link connection 179 carries the pointer with it. The pointer 175 is normally under the control of a spring 180 and when moved in opposition to the spring its action 15 is retarded by a dash-pot 181. When impulses of some certain duration are received by the solenoid 177 then the pointer 178 slowly moves over the index 176 because of the action of the dash-pot 181. In case of 20 an impulse of longer or shorter duration acting on the solenoid 177 the pointer will, because of the dash-pot, be moved to a greater or less extent. If, now, it be understood that a railroad train traveling along the track 25 in one direction shall send out wave trains of a certain duration and a railroad train traveling in the other direction shall send out wave trains of long duration, then it is easily determined from which direction the trains of 30 waves emanated.

The register 151 is best shown in Figs. 6 and 7, where it will be seen that this register includes an electro magnet 182 controlling an armature 183 carrying a visible sign 184 35 which in the drawings is shown provided with the word "Auto". This register is also provided with a spring latch 185 which will engage and hold the armature in the attracted position when the magnets are once energized. The casing of this register has an opaque cover 186 with a sight slot 187 therein through which the sign is visible only when the armature is in the attracted position. This register is sealed by a suitable 40 lock, which can only be opened by an authorized person, so that the engineman is checked against asserting that the train was stopped by the reception of the signals when he himself stopped the train without having received any signals. If the engineman himself stops the train then the circuit of the magnets 140 is broken by the switch 142, which is opened when the throttle is closed, and consequently under these circumstances 50 the register 151 will not operate.

The lamps 72 and 95 and 135 are of course liable to burn out and so may be replaced by a visible signal in the form of a target 188, as shown in Fig. 11, and this target may be operated by a solenoid 189 included in the circuits in place of the lamps.

Since the bells 79 and 105 are of the trembler type they may be caused to ring by yielding of their springs under the shocks 60 and jars incident to the travel of the engine.

For this purpose these bells may have their moving parts locked, when not in action, by a structure such as shown in Fig. 9. In this figure, which is more or less diagrammatic, there is shown the bell magnets 190 included 70 in the usual way in the circuit, and a portion of the armature 191 which carries the hammer is also shown. On this armature there is provided a pin 192 normally in the path of which there is a latch 193 under the control 75 of a magnet 194 permanently included in the circuit and bridging the circuit terminals under the control of the armature 191. When an impulse tending to ring the bell is received, the magnet 194 is energized and pulls 80 the latch 193 from the pin 192 and the armature 191 may respond to the pull of the magnet 190. When the magnets are not energized the latch 193 is in the path of the pin 192 and the armature 191 cannot move to a 85 sufficient extent, under the action of the shocks and jars received from the engine, to bring the hammer into contact with the bell.

In order that the structures may be relieved as far as possible from the effects of 90 the motion of the engine on which they are mounted, there is provided a support, such as shown in Figs. 12 to 14. In this structure there is shown a frame 195 which may be fast to some fixed portion of the engine, and 95 this frame has top and bottom members 196 and 197 joined at the corners of the uprights 198. About midway of this frame there is a platform 199 supporting a casing 200 of sufficient size to inclose the various structures shown in Fig. 1, with the exception of those parts which must be made visible. This platform is supported at each corner by a structure 201 best shown in Fig. 14. This structure comprises a sleeve 202 closed at 100 each end except in one end there is a perforation for the passage of the rod 203 terminating inside of the sleeve in the head 204, and surrounded between the head and the perforated end of the sleeve by a helical spring 105 205. The casing is connected at one end by a ball and socket joint 206 and link 207 to the frame 195 or uprights 198, as the case may be, and the free end of the rod 203 is connected by a ball and socket joint 208 and a 110 link 209 to a corner of the platform 199. Similar structures 201 connect the terminals of the platform to the top and bottom members 196 and 197 of the frame. The platform 199 is thus supported upon spring supports 115 120 in all directions, and, therefore, the entire structure acts in the nature of a shock absorber.

The foregoing description has been confined to two transmitters sending out two 125 trains of waves, one of which overlaps the other at both ends. If under some circumstances it be found advisable, a third transmitter may be employed or a still greater number of transmitters may be employed, 130

and a corresponding number of receivers may be used, the receiving circuits being each differently tuned to the characteristics of the transmitting circuits, it being understood that in the arrangement shown in Fig. 1 the receiving circuits are appropriately tuned. Also there is shown means whereby at least two distinct pairs or groups of trains of waves must be received before the emergency apparatus is rendered active. This is deemed sufficient to show the principle of the invention, but it will be understood that the structures may be multiplied so that three or more pairs or groups of trains of waves must be received in succession before the emergency apparatus is rendered active. These various arrangements are mere multiplications of what is shown in the diagram of Fig. 1, and the arrangement of this diagram may be changed in various ways to meet the exigencies of working conditions so long as the salient features of the invention are included.

It has been heretofore stated that one train of waves is started before the next train of waves, but since the receiving circuits are tuned to the respective characteristics of the waves and the second or succeeding circuits are not complete until the preceding train of waves has had time to act, the trains of waves may be propagated simultaneously since the succeeding train or trains of waves are inactive to the respective receivers until the preceding train or trains of waves have actuated their respective receivers.

In place of the bell 134 and light 135 the engine whistle may be caused to blow continuously so long as the circuit is closed, or if so desired the engine whistle may be added to the bell 134 and light 135 so that the signals are made correspondingly more obtrusive to the engineman.

In order that the plug closing the circuit of the battery 13 may remain normally in place, there is provided a spring 210 tending to always hold this plug in closed position. Attached to the plug is a cord or chain 211, at the end of which is a clip 212 adapted to be placed over the throttle lever so that when a train is side tracked and brought to a standstill, under which conditions it is not necessary to establish a danger zone from the train, then the engineman withdraws the plug against the action of the spring 210 and snaps the clip 212 over the handle of the throttle lever so that when the train is again started this chain and clip will be in the way and the engineman will naturally release the plug from the throttle and again put the apparatus in condition to propagate wave trains.

The rheotome of the Ruhmkorff coil is an unreliable means for making and breaking the primary circuit of the coil, and when the

trains of waves are to be propagated during long periods of time such circuit breakers are liable to give a great deal of trouble and at times fail to work at all. Batteries are also an annoying means for generating electric current, especially under the conditions present upon a locomotive. Of course upon a locomotive engine there is always a steam supply, and consequently the source of current may be a small alternating current 75 electric generator 213 upon which may be mounted the spring contacts 17, 22 and 23, as before, all as shown in Fig. 16. This generator may be driven by a small steam motor 214 which is only indicated diagrammatically in the figure and may be of any type either reciprocating, rotary, or turbine, as may be desired. Since dynamo electric generators of the small type used in connection with this invention are usually run at a 80 rather high speed, say 1500 to 1800 or more revolutions per minute for the armature, and since the number of trains of waves sent out per minute may be small, say four or five or more per minute, the armature shaft 215 carries a worm 216 meshing with a worm gear 217, and through bevel gears 218, 219, 220 and 221, motion is transmitted to a shaft 32 upon which is mounted a disk 38, or it may be the belt 43, as shown in Fig. 5. The dynamo 90 213 avoids all of the objectionable features of the rheotomes of the coils, and these rheotomes are of course omitted as well as the condensers, the coils becoming then an ordinary simple type of inductorium capable 95 of producing currents of very high tension such as are used in wireless transmission of messages or signals.

Upon the shaft of the dynamo 213 are two collecting rings 222, 223, upon each of which 100 bears a brush 224. Leading from the brush upon the ring 222 is a conductor 225 connected to the spring contact 17, and connected to the brush of the ring 223 is a conductor 226 leading to one side of each coil. 110 Interposed in the conductor 226 is a plug switch 227 which may be normally retained in place by a spring 210 and the plug may be connected to a clip 212 by a chain 211, as in the structure shown in Fig. 1, the purpose 115 being to cut out the generator from the coils when the throttle is closed under the conditions mentioned with reference to these parts in the description of Fig. 1. The telephone circuits may be as in the structure shown in 120 Fig. 1, except that there is a battery 227 included in circuit with the transmitter 165 instead of the battery 13 of the system of Fig. 1, and since the coils have no condensers, the condenser cut out at the hook 163 is 125 omitted.

It is a peculiarity of the currents of exceeding high frequency produced by the effect of the spark gap 6 in the circuit that they will follow a metal conductor even 130

though the same be placed directly in contact with the earth, so that the two rails of the railroad, if unconnected by a metallic part, may be utilized as conductors of such currents over considerable distances. In order to utilize this effect as well as the transmission through the air there may be introduced into the aerial 1 a switch 228 by which the coils 4 and 5 may have their secondary boundaries coupled up to a conductor 229 instead of to the aerial, and this conductor ends in a terminal plate 230 close to the ground. In the path of the terminal 230 there may be arranged at intervals along the railroad conducting strips 231, suitably grounded, and the terminals 230 are located close enough to the strips 231, when they pass over them, to permit a spark to leap from the terminal 230 to the strip 231 and thus set up high frequency currents which, together with the currents passing to the rails through the axle 10 may be utilized to energize receivers such as have been described with reference to Fig. 1 and so cause the operation of signals of various types along the line of way. The terminal plates 230 may even be brought into actual contact with the strip 231 since the high frequency currents are generated at the spark gaps 6. There is thus produced a wireless system where the ground instead of the air is utilized for the transmission of the ether waves.

At railway switches and other points where steam or other like power is not available, the coils will be energized by batteries as in the system shown in Fig. 1, and in such case the apparatus will be set in operation only when the switch point is moved to open the siding to traffic and so become dangerous to trains designed to travel over the main track.

At culverts and at other points where the safety of the train may be endangered by cave-ins or washouts or land slides or any other dangerous condition, the apparatus may be installed and may be set into operative condition by weights or other means usually employed for closing electric circuits when such conditions arise.

What is claimed is:—

1. In a wireless railway signal system, means for propagating two or more trains of waves of different characteristics, receiving means each responsive to a respective train of waves, means for producing signals rendered active by one of the receivers and operating continuously independent of said receiver after being once rendered active, and means under the control of the other receiver or receivers for rendering the first-named receiver receptive to the respective train of waves.

2. In a wireless railway signal system, two or more receivers responsive in succession to trains of waves emanating simultaneously

from a source and each receiver controlling the circuit of the next succeeding receiver to render it receptive to the respective train of waves, a signal actuating circuit, and means under the control of the last active receiver 70 for closing the signal circuit.

3. In a wireless railway signal system, a signal circuit having normally open means for closing said circuit, means for imparting to the circuit-closing means an initial movement, which means are under the control of trains of waves emanating from a distant source, and mechanical means for completing the closing of the signal circuit after the initial impulse due to the effect of the received 80 trains of waves.

4. In a wireless railway signaling system, means for sending trains of waves in groups of two or more overlapping trains at predetermined time intervals, means selectively 85 responsive to the individual trains of a group and rendered successively responsive to the wave trains after one of the receivers has been actuated, a signal circuit rendered active by the last receiver to be affected by the 90 trains of waves, and means controlled by the signal circuit for rendering the succeeding circuit active to a succeeding group of two or more overlapping trains of waves.

5. In a wireless railway signal system, 95 means responsive in succession to a group of overlapping trains of waves, two or more circuits each controlling the next succeeding circuit and rendered active in succession by succeeding groups of two or more overlapping trains of waves, and means rendered 100 active by the last circuit made active by the effect of the trains of waves for controlling the railway train operating devices to bring the train to a standstill.

6. In a wireless railway signal system, means responsive to a train of waves, a circuit controlled thereby, another means responsive to a respective train of waves, a circuit including said wave-responsive means, 110 a circuit-controlling means in the second circuit under the control of the first-named circuit, and another circuit under the control of the second circuit and including signal means rendered active by the closure of the 115 third circuit.

7. In a wireless railway signal system, receiving means responsive successively to characteristically different overlapping trains of waves, and a signal circuit controlled 120 and rendered active by the receiving means energized by the last train of waves received.

8. In a wireless railway signal system, receiving means responsive successively to trains of waves, a signal circuit, and means 125 under the control of the last train of waves acting on the receiving means for closing the signal circuit and holding the same closed irrespective of the receiving means.

9. In a wireless railway signal system, 130

- means responsive in succession to overlapping trains of waves, two or more circuits each controlling the next succeeding circuit and rendered active in succession by succeeding trains of waves, and a signal circuit rendered active by the last circuit energized by the wave-train responsive means and at the same time locked out of active relation to the said circuit.
10. In a wireless railway signal system, means rendered successively active by overlapping trains of waves, circuits successively controlled by the wave-train receiving means, a signal circuit responsive to the last circuit rendered active by the trains of waves, and another signal circuit responsive to a succeeding set of overlapping trains of waves while the first signal circuit remains active.
11. In a wireless railway signal system, means responsive successively to overlapping trains of waves, a signal circuit closed by the action of the last received train of waves and remaining closed irrespective of said train of waves, and another circuit, including signal devices, rendered active to another group of overlapping trains of waves while the first-named signal circuit remains closed.
12. In a wireless railway signal system, means responsive to characteristically different overlapping trains of waves, each receptive means controlling the next succeeding receptive means, a signal circuit, means under the control of the last wave-train receptive means energized, for closing and maintaining the signal circuit closed irrespective of the receptive means, and another circuit containing signal and train-controlling means and also under the control of the wave-train

receptive means when the first-named signal circuit is active.

13. In a wireless railway signal system, means responsive in succession to characteristically different overlapping trains of waves, a circuit rendered active by the receiving means controlled by the last train of waves of the group, means under the control of the said signal circuit for placing another circuit in receptive condition, and at the same time producing a signal, with relation to the wave-train receiving means, and train-controlling devices under the control of the last-named means responsive to the wave-train receiving means.

14. In a wireless railway signal system, means responsive in succession to characteristically different overlapping trains of waves, a circuit rendered active by the receiving means controlled by the last train of waves of the group, means under the control of the said signal circuit for placing another circuit in receptive condition, and at the same time producing a signal, with relation to the wave-train receiving means, train-controlling devices under the control of the last-named means responsive to the wave-train receiving means, and a register responsive only when the train-controlling devices have been actuated by received trains of waves.

In testimony that I claim the foregoing as my own, I have hereto affixed my signature in the presence of two witnesses

EDWARD R. BRODTON.
